UNITED STATES PATENT OFFICE.

ROBERT PONTUS LARSEN HYTTE, OF STOCKHOLM, SWEDEN, ASSIGNOR, BY MESNE ASSIGNMENTS, TO THE DE LAVAL SEPARATOR COMPANY, OF NEW YORK, N. Y., A CORPORATION OF NEW JERSEY.

SPEED-REGULATING MEANS FOR MOTIVE-POWER ENGINES.

Application filed July 26, 1920, Serial No. 399,099, and in Sweden August 6, 1919.

In order to render the regulation of the speed of a motive power engine by means of a centrifugal governor sufficiently sensitive, it is necessary that the power of the governor be in a certain relation to the resistance of the regulating member actuated by the governor. In steam engines this regulating member consists either of a throttle-valve, or of a device by means of which the admission 10 to the cylinder is influenced. At any rate, a considerable amount of power is required to bring about the regulation, even if the device is as well balanced as possible. Consequently, the governors often have to be given comparatively large dimensions, which in turn increases the costs and the space required.

The object of the present invention comprises an arrangement whereby the said drawback is reduced, so that a governor of 20 relatively little power may be brought to actuate a regulating member offering considerable resistance to the movements.

The arrangement is distinguished by this that the transmission of the motion from the 25 rotating governor to the regulating member does not take place continually, but intermittently in such a manner that the governor and the regulating member are caused to cooperate with each other during a certain 30 portion of the revolution, while the governor is cut out from such a cooperation during the remaining portion of the revolution. During this latter portion of the revolution the governor may thus move independently of 35 the resistance of the regulating member, in a direction determined by the prevalent change of speed of the engine, after which, when the remaining portion of the revolution is entered upon, a certain impact caused 40 by the inertia of the revolving mass of the governor is actuating the regulating member with a considerable amount of power.

An embodiment of the invention is shown 45 in the accompanying drawing.

a denotes the weights of the governor, the said weights being pivotally mounted on the studs *b* and actuating the sleeve *d* by means of the levers *c*, the sleeve *d* being slidably mounted on the shaft *e* and pressed down- 50 wardly by the helical spring *i*. The said sleeve *d* has guides associated therewith in the form of a pair of flanges *f*, the space between the flanges being occupied by the stud *g* connected to the stem of the admission

valve *h*. The distance between the flanges at 55 part of the circumference corresponds to the diameter of the stud *g*, while at the remaining portion of the circumference the distance between the flanges is greater than the diameter of the stud, as will be seen from the 60 drawing. The transition between the two distances is preferably rounded.

The operation of the device is as follows: If, for example, the engine is unloaded, so 65 that it will have a tendency to increase its speed, the centrifugal power acting on the weights *a* is also increased, whereby the weights tend to move the sleeve *d* upwardly against the action of the spring *i*. If the stud *g* is then within the narrow space between the flanges *f*, the sleeve is pressing 70 against the stud *g*, but not sufficiently to cause a movement of the stud when the change in speed is small, as the centrifugal force exerted is not then sufficient to overcome the friction within the valve, and consequently there will be no axial movement of 75 the sleeve. However, as soon as the governor has revolved so much that the stud *g* is within the space having the greater distance 80 between the flanges *f*, the sleeve *d* can move freely and an axial displacement thereof takes place. When, after the governor has revolved still further, the stud *g* reenters the 85 narrower space between the flanges, it does not fit into its new position, but an impact occurs, in this case between the lower flange and the stud, the consequence of this being a displacement of the stud, in spite of the considerable resistance offered against the 90 movement thereof.

The same cycle of operations is repeated during each consecutive revolution, until the stud has been displaced sufficiently to adjust the admission of steam to the new load 95 on the engine, the governor having then assumed another position of equilibrium corresponding to the new speed.

In the same way the cycle of operations take place on an increase in the load on the 100 engine and a subsequent decrease of the speed.

Evidently, the governor may in this way operate a rather heavy-working valve, as the impacts yield a considerable amount of 105 power, while the governor is free to adjust itself independently of the motive resistance of the regulating member in such a

manner as to cause the impacts to act in the direction called for by the regulation.

The arrangement may of course be modified in various respects, but a condition for 5 the proper operation thereof is that the resistance of the regulating member against the movement thereof be only a passive one.

What I claim as new and desire to secure by Letters Patent of the United 10 States is:—

1. A motive fluid feed control device for engines, comprising a centrifugal governor arranged to be rotated by the engine, a valve movable to regulate the supply of motive 15 fluid to the engine, an element adapted to rotate with the governor and also bodily movable as the speed of the engine varies, a movable member adapted to actuate said motive fluid supply regulating valve, means 20 providing an engagement between said member and element during a part of each revolution of the latter and adapted to restrain said element from bodily movement, and means rotating with said element and 25 adapted, after a bodily movement of said element while free from said restraining means, to engage said member by impact and move it to actuate the motive fluid supply regulating device.
- 30 2. A motive fluid feed control device for engines, comprising a centrifugal governor, a grooved element carried thereby and arranged to be rotated and moved longitudinally along its axis by the governor, a motive fluid control valve, a crank connected to the valve, and a crank pin on the crank extending into the groove of the said grooved element, a portion of the groove being the same width as the crank pin, 35 while the remainder of the groove is wider than the crank pin, the arrangement being such that the grooved element can be moved 40

by the governor without affecting the valve when the crank pin is in the wider portion of the groove while the valve is shifted to 45 the shifted position of the grooved element when the crank pin passes from the wider portion of the groove to the other portion thereof and is retained in such position while the crank pin is in said other portion 50 of the groove.

3. In speed regulating means for engines, the combination with governing mechanism comprising an element centrifugally operable in the operation of the engine, and a 55 rotatable member connected with the centrifugal element and bodily movable as the speed of the engine varies, of a throttling device for regulating the supply of motive fluid to the engine; circumferentially extending guides on the rotatable member presenting relatively closely approximating parallel opposing surfaces along a part of the circumference, opposing surfaces spaced relatively widely apart along another part 60 of the circumference, and relatively short cams each connecting the two specified surfaces of one of the guides; and a stud on the throttling device extending between the guides and, while between the relatively 65 closely approximating surfaces thereof, adapted to hold said member from bodily movement, and, while between the more widely separated guide surfaces, freeing said member for bodily movement, whereby 70 after such bodily movement, one of said cams, in the continued rotation of said member, strikes the stud and shifts the position of the throttling device before the re-entry 75 of the stud between the more closely approximating surfaces of the guides.

In testimony whereof I affix my signature.

ROBERT PONTUS LARSEN HYTTE.
